5,911,504 A 6/1999 Schindlegger, Jr.

DESCRIPTION

FIG. 1 is a front view of a portable blender lid showing the new design;

FIG. 2 is a right-side view thereof;

FIG. 3 is a front-right perspective view thereof;

FIG. 4 is a bottom view thereof;

FIG. 5 is a top view thereof; and,

FIG. 6 is a rear view thereof.

The broken lines in FIG. 4 depict portions of the portable blender lid that form no part of the claimed design.

1 Claim, 6 Drawing Sheets
